DESIGN FOR A SLIDER BODY FOR SLIDE FASTENERS

Noel J. Poux, Meadville, Pa., assignor to Talon,
Inc., Meadville, Pa., a corporation of Penn-
sylvania

Application January 28, 1938, Serial No. 74,680

Term of patent 14 years

To all whom it may concern:

Be it known that I, Noel J. Poux, a citizen of the United States residing at Meadville, in the county of Crawford and State of Pennsylvania, have invented a new, original, and ornamental Design for a Slider Body for Slide Fasteners, of which the following is a specification, reference being had to the accompanying drawing, forming a part thereof.

In the drawing:

Fig. 1 is a face view of a slider body for slide fasteners showing my new design.

Fig. 2 is an end view of the slider body as seen from the right of Fig. 1.

The characteristic feature of my new design resides in the oval shape of the slider body in combination with an elongated panel as it appears in Fig. 1.

I claim:

The ornamental design for a slider body for slide fasteners, as shown and described.

NOEL J. POUX.
